UNITED STATES PATENT OFFICE

EDGAR SCOFIELD, OF NEW YORK, N. Y., ASSIGNOR TO ANCHOR CAP & CLOSURE CORPORATION, OF LONG ISLAND CITY, NEW YORK, A CORPORATION OF NEW YORK

HERMETICALLY-SEALED PACKAGE

Application filed June 16, 1928. Serial No. 285,811.

The present invention relates generally to the sealing art and more particularly to improvements in hermetically sealed packages having seals formed on the side wall of the container, for example, packages similar to that shown in my Patent No. 1,611,955 granted December 28, 1926.

The side walls of glass containers are usually free from defects common to the edges thereof, hence side seal closures form seals superior to other types. Due to the fact that these seals are usually formed on the straight side wall of containers, a very tight seal is necessary to hold the caps in position. Most products must be kept hermetically sealed for months and, in some cases, for years. This is another reason for a tight seal.

Side seals are generally made by mechanically reforming the skirt of the cap and constricting it about the gasket to compress the gasket tightly against the container. The metal of the cap frequently crinkles during the constricting operation, detracting from the appearance of the cap and rendering the seal less perfect. Pressures of several thousand pounds are required for the reforming and sealing operation. Caps thus securely applied are difficult to remove because of the tightness with which they are secured to the container and because the lower edge of the cap is constricted closely about the container making it difficult to apply instruments to the cap for removal thereof. Consumers, inexperienced in the characteristics of the cap, distort it during removal to such an extent that it cannot be used for re-seal purposes.

The present invention aims to overcome or minimize these difficulties by providing a cap and package which may be securely sealed as heretofore by means of lower pressures without crinkling the metal of the constricted part of the cap. The skirt of the cap facilitates the application of a removing tool adapted to engage the bottom of the skirt at consecutive points throughout the periphery thereof to expand the skirt for removal without material deformation thereof. The cap, when thus removed, may be used sub-

sequently for re-seal purposes, that is, to close the container during consumption, from day to day, of the product therein.

An object of the invention is to facilitate application and removal of side seal closures without impairing the effectiveness of the seal. 55

Another object of the invention is to provide a side seal closure cap which may be readily removed and used thereafter for re-seal purposes. 60

A further object of the invention is to eliminate crinkling of the metal caused by the constriction of the skirt of the cap about the gasket during the sealing operation. 65

Other and further objects of the invention will be obvious upon an understanding of the illustrated embodiment about to be described or indicated in appended claims, and various advantages not referred to herein will occur to one skilled in the art upon employment of the invention in practice. 79

A preferred embodiment of the invention has been chosen for purposes of illustration and description and is shown in the accompanying drawings, wherein 75

Fig. 1 is a side elevational view, partly in section, of a sealed package illustrating the application of the invention thereto;

Fig. 2 is an enlarged elevational view of 80 a portion of the package showing one of the slits;

Fig. 3 is a partial sectional view along the line 3—3 of Fig. 1;

Fig. 4 is a sectional view of a blank adapted 85 to be formed into a cap;

Fig. 5 is a side elevational view partly in section showing a cap and gasket assembled;

Fig. 6 is a partial sectional view illustrating 90 the removal of the cap; and

Fig. 7 is a sectional view of another form of the invention.

Referring to the drawings, there is shown a container 1, which is here shown in the form of a tumbler, with a substantially cylindrical side wall sealing surface adjacent its upper end. A closure cap 2 with a gasket 4 in the skirt thereof, as shown in Fig. 5, may be applied to the upper end of the tumbler. When in unsealed position, the closure cap com- 95

prises a cover portion 5 and a depending skirt 6 with a bead 7 formed therein to receive the gasket. The lower edge of the skirt is turned inwardly to form the lower side of the bead 5 and to form also a supporting shelf for the gasket. Such a cap may be made in any suitable manner. For example, it may be stamped by means of a combination die into a form such as that shown in Fig. 4. The die is 10 such that the lower edge of the blank has a series of slits 8 therein preferably at equal intervals throughout. Thereafter, the lower edge is turned inwardly as shown in Fig. 5, so that a gasket 4 may be assembled and held 15 in position by the lower edge.

In the sealing operation the shape of the bead 7 is changed from the form shown in Fig. 5 to that shown in Fig. 1. In this reforming operation, the outer side of the bead 20 is pressed inwardly and the lower part thereof is constricted in size to press the gasket firmly against the side wall of the container. Such constricting operation is usually performed by means of a chuck and there is 25 considerable tendency for the metal to crinkle in the constricting operation. In other words, the resistance to the compression of the metal in the reduction of size is so great that the metal will sometimes bend inwardly 30 to form what may be called a kink which presses into the gasket. Such crinkles or kinks not only mar the appearance of the cap but likewise affect the security of the seal. In addition, the lower part of the 35 skirt, when sealed, presents a band of metal about the lower part of the gasket which is in very close proximity to the side wall of the container. This makes it difficult to apply an instrument since the space between the 40 bottom of the skirt and the side wall of the container is very small. Furthermore, after the cap opener is applied, it is necessary to exert sufficient pressure to stretch this band of metal. Where an ordinary hook opener is 45 used, the cap is stretched at one point only and considerable difficulty may be encountered in its removal. Then too, the pressure necessary for stretching the band of metal in the bottom of the cap distorts the other parts 50 of the cap so that it is destroyed and cannot be used for re-seal purposes.

By providing the slits 8, the lower side of the gasket is held by a plurality of independent holding members 9 intermediate the slits. 55 In the sealing operation, the constriction of the metal may be readily achieved since the slits accommodate the change in size. There is no tendency for the metal to crinkle and less pressure may be used in the sealing operation. The slits extend but a short distance 60 from the bottom of the cap; hence, ample metal remains for forming a tight seal on the container. The bottom of the skirt, due to the slits, does not hug the side wall of the 65 container so closely but spreads outwardly to

afford a greater space between the bottom of the skirt and the container for the application of a cap opener.

While the cap may be removed by the application of an opener at any point, preferably the opener is applied to the consecutive segments 9 which are pulled outwardly as shown in Fig. 6 to expand the lower part of the skirt of the cap and permit its ready removal. This can be achieved without marring the appearance of the cap and without destroying it. In fact, the expansion of the skirt as shown increases the size of the gasket to a point where it will telescope tightly over the container and may be put on and off 70 75 indefinitely manually to form a liquid-tight and in some instances, an hermetic seal.

While any suitable slot may be used, preferably the shape of the slots 8 is narrow and of such depth that they extend but a short distance above the lower edge of the skirt. The width of the slot is preferably slightly greater than the amount required to take up the reduction in diameter of the lower part of the skirt without necessitating material 80 85 compression of the metal at this point.

The invention is shown in Fig. 7 applied to another form of package in which the lower part of the skirt of the cap is constricted to press the gasket against the container and is also bent inwardly to form an in-turned flange 10 for supporting the bottom of the gasket. By slitting this cap as shown at 11 the bottom of the gasket will be held 90 in position by a series of independent holding members which may be readily bent outwardly to facilitate removal of the cap. Preferably the slots 11 extend slightly above the flange 10.

It will be seen that an economical one-piece side seal closure cap has been provided which may be more easily applied and removed with less difficulty than heretofore. Further, the cap is adapted to be used as a re-seal closure during consumption of the 105 contents of the package. The application of the invention to the present forms of commercial closures does not present serious difficulties, since the dies may be readily changed to slit the edges of the blank during 110 the stamping operations and hence no additional operations are necessary. A substantial band of metal is effective to press the gasket against the container and, therefore, the tightness of the seal is not affected by 115 the slits. In the case where the bottom of the cap is supported, the inturned metal is sufficient to hold the gasket in place with the slots in the cap, and hence in these closures also the seal is not impaired in any 120 way. The cost of the closures is not increased, the sealing operation is simplified 125 since lower pressures may be used, and the removal of the cap is materially facilitated without impairing the seal.

As various changes may be made in the above embodiment without departing from the spirit of the invention it is to be understood that all matter herein is to be interpreted as illustrative and not in a limiting sense.

Having thus described my invention, I claim:

1. A closure cap comprising a cover portion, a depending skirt, and a bead formed in said skirt adapted to receive a gasket, the lower side of said bead having a series of slits therein.

2. A closure cap comprising a cover portion, a depending skirt, a bead formed in said skirt, a gasket in said bead, the lower side of the bead having slotted portions to facilitate reformation of said bead in the sealing operation and to facilitate constricting the circumference of the lower side thereof.

3. A sealed package comprising a container having a substantially incompressible side wall and a closure cap, a gasket in the skirt of the cap compressed between the skirt and the side wall of the container, the part of the skirt holding the lower part of the gasket being slotted at intervals to facilitate removal of the cap.

4. A sealed package comprising a container, having a substantially incompressible side wall, a closure cap, a gasket in the skirt of the cap compressed between the skirt and the side wall of the container, and a plurality of independent sections separated by narrow slits adapted to hold the lower edge of said gasket in position.

5. A hermetically sealed package comprising a container having a substantially incompressible side wall, a closure cap having a bead in the skirt thereof, a gasket in said bead compressed against the side wall of the container, the lower side of the bead having a series of slits forming independent holding members for the lower part of the gasket, whereby these members may be pulled outwardly to release the gasket and to remove the cap without necessitating the stretching of the metal at the edge of the cap.

6. A hermetically sealed package comprising a container having a substantially incompressible side wall, a closure cap having a bead in the skirt thereof, a gasket in said bead compressed against the side wall of the container, said gasket being held in position at the lower side thereof by a plurality of members independently bendable whereby the lower part of the skirt may be readily expanded at consecutive portions of its periphery without material deformation, thereby permitting it to be used as a re-seal.

7. A closure cap comprising a cover portion and a depending skirt, the bottom of said skirt being turned inwardly to form a support for a ring gasket, with the free edge 65 of the inturned skirt severed at a plurality

of points about its periphery, and a ring gasket in said skirt adjacent said slotted portions.

8. A closure cap comprising a cover portion and a depending skirt, the bottom of said skirt comprising a series of segments bent inwardly to support a ring gasket, and a ring gasket in the skirt of said cap seated upon said segments.

9. As an article of manufacture, a closure cap comprising a cover portion, a depending skirt shaped to receive a ring gasket, with the lower edge of the skirt turned inwardly to support said gasket, said lower edge being slotted at intervals to facilitate the reformation thereof for forcing the gasket inwardly toward the side wall of a container in the sealing thereof.

Dated: New York, N. Y., June 6, 1928.
